UNITED STATES PATENT OFFICE.

JOHN R. SWANSON, OF ROCK ISLAND, ILLINOIS.

AUTOMATIC BOILER-FEED RETURN APPARATUS.

Application filed May 6, 1926. Serial No. 107,107.

My invention has reference to an automatic feed return apparatus for boilers, of that type which is set forth in Letters Patent of the United States No. 1,539,883, 5 issued to myself June 2nd, 1925, and for additional improvements in which I made application for Letters Patent of the United States under date of May 12, 1924, Serial No. 712,744. One of the chief uses thereof 10 is in a plant or building in which there is a system of steam heating radiation, for carrying the products of condensation back to the boiler, but it may be used in other places, such as laundries and the like. By its use 15 the water is maintained at a uniform height in the boiler containing the main supply. Said former invention was dependent for its operation upon a pair of tanks, one of which would be filling with water while the other 20 was being emptied. One of the purposes of the present invention is to perform the same work by the use of a single tank, thus greatly simplifying the device and the operation thereof. The use of objectionable 25 and faulty packing boxes is also done away with.

In said former patent there is set forth a novel steam control mechanism for admitting successive charges of steam to the tanks 30 for use in expelling the water therefrom, and one of the objects of the present invention is to simplify said control mechanism and increase the efficiency thereof, in its application to the single tank system mentioned.

While the present invention is based upon a one tank system, the capacity can be doubled, if desired, by using two of said tanks coupled up with one of the water control valve systems set forth in said application of May 12, 1924. Said valve system included a float and lever control of the valves, but in the present apparatus this would not be required with the use of the 45 single tank.

In the use of the single tank quantities of water are at times contained therein, alternating with volumes of steam under relatively high pressure, and the arrangement and operation of the machine is such that the steam force can at no time interfere with the action of the water, in entering the tank, nor follow the same out of the tank, when the water is expelled therefrom. 50 It has been found to be impractical to use

hollow floats in devices of the class named where there is a great amount of steam pressure, as such floats contain joints and seams which require soldering, and which soldering becomes ineffective under relatively high temperatures, permitting the water to enter the floats, and destroying the usefulness thereof. In the present invention other types of floats are substituted therefor, with a satisfactory operation under all heat 60 conditions.

The above named and other features and advantages of the invention will be more fully understood from the following specification, reference being had to the accompanying drawings, in which;—

Fig. 1 shows the invention in front elevation.

Fig. 2 is a detail of the rock-shaft 34, with parts in section.

Fig. 3 is a detail of the relief cock 23, in longitudinal section.

Fig. 4 is a vertical medial section of the invention.

Fig. 5 is an enlarged view of the steam 80 control cylinder, in longitudinal section.

The invention comprises a tank 1, supported on a base 2, containing a bowl 3 forming the lower part of the tank, which is connected by a pipe 4 with a boiler, or 85 some part of a plant containing a boiler and steam system. The pipe 4 is provided with a check-valve, as at 5, which permits the movement of water through said pipe in a direction away from the tank but prevents 90 its return thereto.

Supported above the tank 1 is a dome 6, having a lateral extension 7, entering which is a pipe 8, the other end of which is connected with a receiving tank or system of 95 radiation, the water in which will find its way through said pipe into the tank 1, being impelled by gravity or a limited amount of pressure, or both. The pipe 8 is provided with a check-valve at 9, of a character to 100 prevent the movement of water or steam outwardly through said pipe.

At the upper end of the dome 6 is a plate 10, upon which is supported a cylinder 11, connected at a central point of which is a 105 pipe 12, leading from a point above the water line of a boiler. In the opposite ends of the cylinder 11 is a pair of hollow pistons 13 and 14, united by a rod 15, and adapted for operation alternately toward opposite ends 110

of the cylinder. The adjacent ends of said pistons are of reduced diameters, and each thereof is provided with a small perforation 16, while in the ends of said pistons are several openings 17 of greater size than the perforations 16. Between the pistons 13 and 14 is a slide-valve 18, having a recess 19 in its lower side, said valve being adapted for the alternate opening and closing of a passage 20 connecting the cylinder 11 and dome 6. The plate 10 is also provided with a passage 21 extending partly through the same and then out at one side, permitting the escape of exhaust steam contained in the tank when the slide-valve is in the position shown in Fig. 4.

Projecting outwardly from one side of the cylinder 11, near the ends thereof, is a pair of relief cocks 22 and 23, (Fig. 1) in each of which is a passage 25, divided by a partition 26, in which is a circular opening normally closed by the end of a valve 27 in a tubular extension 28 of the cock. Each valve is connected by a link 29 with the short arm of a bell-crank lever 30, pivoted in the end of the extension 28. Pivoted at its upper end to the side of the cylinder 11 is a lever 31, positioned midway the levers 30, and provided with a cross-arm 32, the ends of which bear against said levers. Supported from the end of the extension 7 is a bearing 33, in which is rockingly mounted a shaft 34, to the outer end of which is fixed an arm 35, connected by a link 36 with the free end of the lever 31. By a means hereinafter set forth the shaft 34 is rocked to cause a movement of the lever 31 to actuate one or other of the levers 30, to open the relief cock valve with which said lever is connected. When the pistons 13 and 14 are in the positions shown in Figures 4 and 5 a volume of steam coming in through the pipe 12 finds its way slowly through the perforation 16 in the piston 14, until the pressure thereof tends to force the piston inwardly in the cylinder. This is prevented, however, by an equal force in the opposite end of the cylinder. Upon the cock 22 being opened this latter force is relieved and a quick action of the pistons follows. This movement is accelerated by the passages in the end of the piston 14, which permit a rapid movement of the steam into the end of the cylinder 11. At the end of a desired period the cock 23 is again opened and the pistons return to the positions shown in said figures.

The lever 31 is actuated by the following means;—On the inner end of the shaft 34 is an enlargement 37, to which is attached one end of an arm 38, the other end of which is secured to the upper end of a tubular rod 39, the lower end of which is slidable on a guide-rod 40. Supported on the upper end of the rod 39 is a float 41, formed of relatively light metal, such as aluminum, which

is held in position by a nut 42 on a threaded portion of the rod. Fixed to the lower end of the rod 39 is a bucket 43.

When the slide-valve 18 is in the position shown in Figures 4 and 5 water is permitted to enter the tank 1 through the pipe 8, the exhaust steam or air which is displaced thereby being forced out through the passages 20 and 21. Upon the water reaching the top of the tank the float 41 is raised thereby, elevating the arm 38 and rocking the shaft 34 in a direction to cause the opening of the cock 22. This permits a movement of the pistons to open the passage 20 to the steam in the cylinder 11, and at the same time close the exhaust passage 21. The pressure of the steam, together with the gravity of the water carries the water downwardly in the tank 1, and out through the pipe 4 to the boiler. So long as the bucket 43 is covered by the main body of water in the tank such bucket and its contents will be buoyed up thereby, but upon the water line in the tank falling below the bucket the weight of such bucket and the water therein will pull the rod 39 downwardly, rocking the shaft 34 in a direction to cause the opening of the cock 23. Meanwhile steam through the pipe 12 has been entering the piston 13 through the perforation 16 therein, and upon the cock 23 being opened the pistons shift instantly toward the opposite end of the cylinder to that in which they have been positioned. This at once cuts off all communication between the cylinder and tank, and prevents the steam from following the water into the pipe 4. It also instantly opens the exhaust, so that there can be no interference of the pressure of the steam in the tank with the water coming in through the pipe 8.

To prevent the weight of the float 41 from causing the rod 39 to move downwardly prematurely the lever 31 is provided with an arm 44, at the end of which is a weight 45, said arm and weight counterbalancing the weight of the float. When the water first enters the tank and rises as high as the bucket 43 the weight 45 will serve to bring the ball 41 and rod 39 into the position shown in Fig. 4, with the lever 31 in a vertical line and both of the cocks 22 and 23 closed. As the water continues to rise in the tank it buoys up the ball 41, and the weight 45 assists in rocking the shaft 34 in the operation of opening the cock 22. When the water is forced from the tank 1 the ball 41 returns to the position shown in Fig. 4 as soon as the water falls below the same, and the lever 31 is again held in a neutral position. As the water line reaches the lower part of the tank the bucket 43 is uncovered and said bucket and the rod 39 move downwardly with the water, as before mentioned. The greater part of the time, when the tank is either filling with water or with

steam, the lever 31 is in a neutral position, the shifting of the pistons in one direction or the other being alternated by intervals of rest, which are terminated by the action of 5 the water itself, either in filling or emptying the tank.

The levers 30 are united by a tension spring 46, which acts in both directions, and holds the valves 27 from being opened by 10 the force of the steam in the relief cocks when the lever 31 is in a neutral position.

The end of the enlargement 37 is rounded, and machined to fit snugly into a similarly shaped recess in the inner end of the bearing 33, a tight bearing being thereby secured, which will prevent the passage of 15 water or steam.

The invention can be employed in any system wherein there is a back pressure or 20 gravity return of the water, and no trap or back return valves are required to be used therewith, aside from the check-valves 5 and 9.

What I claim, and desire to secure by 25 Letters Patent, is;

1. A device of the class described, comprising a tank having a water intake and a water outlet, a steam control mechanism connected with said tank, relief cocks and 30 valves therefor for said steam control mech-

anism, bell-crank levers connected with said valves and provided with yieldable connecting means, a shift lever adapted for alternate operation of said levers, a water controlled mechanism in said tank, an arm rock- 35 ingly mounted in said tank and operatively connected with said last-named mechanism, and mechanism connecting said arm with said shift-lever, to impart the movement of said arm thereto.

2. A device of the class described, comprising a tank having a water intake and a water outlet, a vertically movable rod in said tank provided with a float member at its upper end and a weight at its lower end, 45 a cylinder mounted on said tank having a central steam intake and a passage into said tank, steam control devices in said cylinder for admitting successive charges of steam into said tank, relief valves connected with 50 said cylinder and spring-actuated levers therefor, a lever adapted for alternate engagement with said first-named levers, means for imparting the movement of said rod to said last-named lever, and a weight 55 counterbalancing the weight of said float.

In testimony whereof I affix my signature.

JOHN R. SWANSON.
